(57) **CLAIM**

What is claimed is the ornamental design for a personal enclosure, as shown and described.

DESCRIPTION

FIG. 1 is a perspective view of a personal enclosure; FIG. 2 is another perspective view of the personal enclosure of FIG. 1;

FIG. 3 is a front view of the personal enclosure of FIG. 1; FIG. 4 is a rear view of the personal enclosure of FIG. 1; FIG. 5 is a left side view of the personal enclosure of FIG. 1;

FIG. 6 is a right side view of the personal enclosure of FIG. 1;

FIG. 7 is a top view of the personal enclosure of FIG. 1; and, FIG. 8 is a bottom view of the personal enclosure of FIG. 1. The broken lines in the drawings show stitching that is included in the claimed design.

1 Claim, 7 Drawing Sheets
